UNITED STATES PATENT OFFICE.

ADOLPH D. KETCHER, OF AKRON, OHIO.

DESIGN FOR A DISH.

48,340.

Specification for Design. Patented Dec. 21, 1915.

Application filed August 18, 1915. Serial No. 46,197. Term of patent 3½ years.

To all whom it may concern:

Be it known that I, ADOLPH D. KETCHER, a citizen of the United States, residing at Akron, in the county of Summit and State of Ohio, have invented a new, original, and ornamental Design for Dishes, of which the following is a specification, reference being had to the accompanying drawings, forming part thereof.

In the drawings, Figure 1, is a plan view of a dish illustrating my new design, and Fig. 2, an inverted plan view.

I claim:

The ornamental design for a dish, substantially as shown.

ADOLPH D. KETCHER.
